UNITED STATES PATENT OFFICE.

ROBERT N. FLANAGAN, OF CHARLOTTESVILLE, VIRGINIA, ASSIGNOR TO
SAID ROBT. N. FLANAGAN AND CHARLES CARROLL, OF BALTIMORE,
MARYLAND.

MACHINE FOR SEWING LEATHER.

SPECIFICATION forming part of Letters Patent No. 792,576, dated June 13, 1905.

Application filed August 30, 1904, Serial No. 222,689.

To all whom it may concern:

Be it known that I, ROBERT N. FLANAGAN, a citizen of the United States, residing at Charlottesville, in the county of Albemarle 5 and State of Virginia, have invented certain new and useful Improvements in Machines for Sewing Leather; and I do declare the following to be a full, clear, and exact description of the invention, such as will enable 10 others skilled in the art to which it appertains to make and use the same.

This invention relates to improvements in machines for sewing leather or other thick heavy material.

15 The object of the invention is to provide a machine of this character whereby sole-leather or other heavy material may be neatly and evenly sewed or stitched together.

A further object is to provide means where- 20 by the stitches made by said machine may be lengthened or shortened, means being also provided whereby the feeding mechanism will be positively and evenly operated at all times.

25 Still another object is to provide a machine of this character which will be simple in construction, strong, durable, and well adapted to the purpose for which it is designed.

With these and other objects in view the 30 invention consists of certain novel features of construction, combination, and arrangement of parts, as will be hereinafter more fully described, and particularly pointed out in the appended claims.

35 In the accompanying drawings, Figure 1 is a side view of the machine. Fig. 2 is a top plan view. Fig. 3 is a vertical sectional view taken on a line with the needle-bar, and Fig. 4 is a detail view of the mechanism for 40 feeding or moving the material being sewed.

Referring more particularly to the drawings, 1 denotes a base upon which is mounted a suitable frame 2. Said frame 2 consists of a pair of horizontally-disposed bars 3, 45 which are connected at their rear end by a cross-bar 4 and at their forward ends are connected to or formed integral with a vertically-disposed plate 5. The lower edge of the

plate 5 is screwed or otherwise secured to the base 1. The cross-bar 4 is connected to the 50 upper end of a supporting leg or standard 6, which is bolted or otherwise secured at its lower end to the base 1.

The bars 3 are connected midway between their ends by an intermediate cross-bar 7. 55 In the cross-bar 7 is formed a guide passage or opening 8. In the cross-bar 4 is also provided a guide-passage 9. The passages 8 and 9 are in alinement, and in the same is slidably mounted a needle-carrying bar 10, 60 on one end of which is arranged a needle-clamping device 100. In the opposite end of the bar is formed a notch through which is adapted to be passed a thread 13. The thread 13 extends from a spool which is suitably 65 mounted on a pin 14, fixed to the base 1. From the end of the needle-bar the thread 13 passes around a tension device 15 and from thence through a guide-eye 16 to the needle 17. The needle 17 is secured in the outer 70 end of the needle-bar 10.

The tension device 15 consists of a bolt 18, which is secured to and projects laterally from the rear side of the cross-bar 4, and on said bolt is fixedly mounted a convex disk 19, 75 and on the bolt 18 is also loosely mounted a convex disk 20. On the outer end of the bolt 18 is formed threads, and on said end is adapted to be screwed a nut 21. Between the nut 21 and the disk 20 is arranged a coil-spring 22, the tension of which is normally exerted to force the loosely-mounted disk 20 into engagement with the disk 19 on said bolt, and between the disks is adapted to pass the thread 13. By screwing the nut 21 inwardly or outwardly on the bolt 18 the tension of said spring will be regulated to cause the disks to more or less tightly engage said thread.

On the upper edge of the plate 5 is slidably 90 mounted a toothed rack-bar 23, on the under side of which is formed a longitudinally-disposed groove or channel 24. The groove or channel 24 is adapted to engage the upper edge of the plate 5, thereby holding said bar 95 against lateral movement on said plate. On

the outer side of the bar 23 is formed a downwardly-projecting flange to which is secured the upper end of a leather holding or clamping device 25. Said clamping device consists of an inner jaw or plate 26, fixedly connected at its upper end to the flange of said rack-bar. To the lower end of said fixed jaw or plate 26 is connected the lower end of a movable jaw or plate 27. Said plates are spaced apart at their lower or connecting ends by means of a spacing-block 28. In the inner plate 26 is arranged a headed bolt 29, the outer end of which is adapted to project through the outer plate or jaw 27. Upon said outer end is screwed a clamping-nut 30, which when screwed inwardly upon said bolt is adapted to force the outer jaw-plate toward the inner jaw-plate, thereby clamping between the same the leather or other material being stitched.

On the intermediate cross-bar 7 is mounted a pivoted bar 31, on the inner end of which is pivotally mounted an operating-lever 32. The inner end of the lever 32 is pivotally connected to the needle-bar. When said operating-bar is swung upon the bar 31, said needle-bar will be reciprocated backwardly and forwardly through the bars 4 and 7 to force the needle carried by the outer end of the same through the leather or other material held by said clamping device.

In order that the clamping device carrying the material to be sewed may be shifted or fed along the plate 5 as the stitches are formed in the same, a suitable feeding mechanism is provided. Said feeding mechanism consists of a block 33, which is fixedly mounted on the outer end of an arm 34, said arm being pivotally mounted at its opposite end on the intermediate cross-bar 7.

In the outer end of the bar 31 is formed a series of apertures 35, to one of which is pivotally connected an arm or link 36, the opposite end of which is pivotally connected to the arm 34 adjacent to the block 33, so that when the lever 32 is operated to actuate the needle-bar said arm 34 and block 33 will be rocked backwardly and forwardly above the rack-bar 23. The lower side of the block 33 is recessed at its outer end, and in said recess is pivotally mounted a series of pawls or dogs 37. The dogs or pawls 37 are adapted to engage the teeth on the rack-bar 23, so that when said block 33 is moved in one direction the pawls or dogs 37 will play loosely over the teeth of said rack-bar, and when said block is moved in the opposite direction said pawls will engage the teeth of the rack-bar, thereby forcing said bar and leather-clamping devices carried thereby along the plate 5, thus feeding the material along in front of the needle, so that the same may form even stitches in said material. In order that the length of the stitches may be changed, the pivotal con-

nexion of the link 36 with the bar 31 may be shifted from one to another of the apertures 35, thereby increasing or diminishing the swing of the arm 34 and the movement of the block 33, thus causing the rack-bar and holding device to be moved to a greater or less degree at each movement of said block 33, thereby causing stitches to be formed of greater or less length. In order that the shifting or feeding of the rack-bar will not be affected by the adjustment of the stitch-changing mechanism, the pawls or dogs 37 are formed of different lengths, so that at least one of the same will always engage the teeth of the rack-bar.

In operation the leather to be stitched is clamped between the jaws or plates 26 and 27 of the clamping device and the rack-bar 23 adjusted to bring the edge of said leather to a position opposite the end of the needle. The operating-lever is now actuated to reciprocate the needle-bar, and thereby forcing the needle through the leather. The free end of the thread is now grasped and drawn through the needle-hole in said leather and is clamped or caught beneath a holding device 38, which is secured to the outer side of the jaw 27 and preferably consists of a spring steel plate bent upon itself to form clamping-jaws, between which the end of the thread is caught. The plate is secured to said jaw by means of a bolt 39, which passes through said jaw and holding device, and on the outer end of the bolt is adapted to be screwed a nut 40, by which the jaws formed by the ends of the plate are clamped together. After the needle has been forced through the leather at the beginning of the seam the same is retracted and again forced through, carrying therewith a loop of the thread. Through said loop is adapted to be passed the end of the thread which was carried through the leather by the former operation of the needle. The needle is now retracted again, thus drawing the loop of the thread into tight engagement with the end of the same, thereby forming a stitch, this operation being repeated for each successive stitch formed by the machine.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of this invention.

Having thus described my invention, what I claim as new, and desire to secure by Letters Patent, is—

1. In a machine of the character described, the combination of a needle-bar, a movable work-holder, a swinging bar, a lever pivotally connected thereto and to the needle-bar,

a rock-arm, a link connecting the rock-arm and the swinging bar, a rack connected to the movable work-holder, and a pawl movable with and by the rock-arm and coacting with the rack to impart step-by-step movement to the work-holder.

2. In a machine for sewing leather, the combination with a suitably-mounted frame, of a needle-bar slidably mounted in the same, an operating-lever pivotally connected to said frame and needle-bar to operate the latter, a leather-holding clamp slidably mounted on said frame, feeding mechanism whereby said leather-holding device is moved along to permit the formation of stitches, and means whereby said feeding mechanism is adjusted to change the length of said stitches, substantially as described.

3. In a machine for sewing leather, the combination with a suitably-mounted frame, of a needle-bar slidably mounted in the same, an operating-lever pivotally connected to said frame and needle-bar whereby the latter may be reciprocated, a rack-bar slidably mounted on said frame, a leather-holding device fixed to said rack-bar, a rocking element pivotally mounted on said frame and having a pawl to engage said rack-bar, and means actuated by said operating-lever to operate said rocking element, substantially as described.

4. In a machine of the class described, the combination of a needle-bar, a movable work-holder, a swinging bar, a lever pivotally connected thereto and to the needle-bar, a rock-arm, a link connecting the rock-arm and the swinging bar, a rack connected to the movable work-holder, a pawl movable with and by the rock-arm and coacting with the rack to impart step-by-step movement to the work-holder, and means to vary the length of the stroke of the rock-arm, substantially as described.

5. In a machine of the character described, the combination of a needle-bar, a movable work-holder, a swinging bar, a lever pivotally connected thereto and to the needle-bar, a rock-arm, a link connecting the rock-arm and the swinging bar and adjustable angularly with respect to one of them to vary the stroke of the rock-arm, a rack connected to the movable work-holder, and a

pawl movable with and by the rock-arm and coacting with the rack to impart step-by-step movement to the work-holder.

55

6. In a machine for sewing leather, the combination with a suitably-mounted frame, of a needle-bar slidably mounted in the same, a pivotally-mounted bar arranged on said frame, one end of said bar having formed therein a series of vertically-disposed apertures, an operating-lever pivotally connected to the opposite end of said bar and to said needle-bar, whereby the latter may be operated, a rack-bar slidably mounted on said frame, a leather-holding device carried by said rack-bar, an arm pivotally mounted on said frame, pivoted pawls carried by said arm, said pawls being of different lengths, a link pivotally connected at one end to said arm, the opposite end of said links being pivotally and adjustably connected in one of the apertures of the pivoted arm to which said operating-lever is connected, whereby when said operating-lever is moved said arm will be actuated to cause said pawls to engage said rack-bar, substantially as described.

7. In a machine for sewing leather, the combination with a suitably-mounted frame, of a needle-bar slidably mounted in the same, an operating-lever mounted in said frame to reciprocate said needle-bar, a rack-bar slidably mounted on said frame, a leather-holding device carried by said rack-bar, an arm pivotally mounted on said frame, a block fixed on said arm, pawls pivotally mounted in said block to engage said rack-bar, said pawls being of different lengths, mechanism actuated by said operating-lever, to swing said arm and block, thereby causing one or more of said pawls to engage the teeth of said rack, and means whereby the swinging movement of said arm and block is regulated to cause the same to shift said rack-bar to a greater or less degree thereby changing the length of the stitches formed by the needle, substantially as described.

In testimony whereof I have hereunto set my hand in presence of two subscribing witnesses.

R. N. FLANAGAN.
